(57) **CLAIM**

The ornamental design for a distal end of mounting bracket for DAS antenna, as shown and described.

DESCRIPTION

FIG. 1 is an isometric right front side view of a distal end of mounting bracket for DAS antenna according to the present design;

FIG. 2 is an isometric left front side view thereof;

FIG. 3 is a top view thereof;

FIG. 4 is a bottom view thereof;

FIG. 5 is a front view thereof;

FIG. 6 is a bottom view thereof;

FIG. 7 is a right side view thereof; and,

FIG. 8 is a left side view thereof.

Elements shown in dotted lines are environmental structure that form no part of the claimed design.
